WELL TESTING TOOL

William K. Ansite, Glendale, Calif., assignor to Johnston Testers, Inc., Houston, Tex., a corporation of Texas

Application October 10, 1956, Serial No. 615,160

11 Claims. (Cl. 166—226)

This invention relates to well testing tools and, more particularly, to well testing tools having a combination of functions.

In making a test of a formation where the connate fluid is under high pressure, it is desirable to progressively open the tool to the upward flow of fluid therethrough so as to prevent damage to the tool which might be caused by high velocity fluid jetting uncontrolled through the tool. Also, after the test is made and the sample collected, it is frequently desirable to be able to make a shut-in test, that is, to take the pressure of the fluid in the formation with the bore above the formation completely closed off by the tool. Furthermore, frequently it is desirable to reversely circulate drilling mud or other liquid down the well around the exterior of the string of pipe supporting the tool and then into the tool and upwardly through the pipe for the purpose of bringing connate fluid to the surface, and also for various other purposes.

It is a main object of the present invention to provide a simple and inexpensive tool by which the three operations above described may be readily carried out.

It is a more particular object of the present invention to provide a tool by which the above-named operations may be carried out in the sequence above enumerated, and by merely rotating the string of pipe supporting the tool to effect such a sequence of operations.

According to the present invention, a well tool is provided having a housing for connection with a packer and a tubular mandrel rotatable within the housing for connection with a pipe string extending from the surface. A valve sleeve slidably non-rotatively within the bore of the housing is moved relative to test ports in the mandrel by rotation of the mandrel so as to control flow of fluid through the test ports. In an initial position, a portion of the sleeve is sealed across the test ports to block a flow of fluid. In a second position, the sleeve affords communication between the interior of the mandrel and the well below the packer through restricted choke orifices. Upon further movement of the sleeve, fully open passages in the sleeve afford communication in lieu of the choke orifices. Further movement of the sleeve closes the test ports, and yet further movement may be provided for reopening the test ports and also opening circulating ports in the housing to permit reverse circulation.

The invention will be better understood from the following detailed description taken in conjunction with accompanying drawings, in which:

Fig. 1 is an elevational cross-sectional view of a preferred embodiment of the invention showing the parts in relation to provide an initial shut-in pressure test;

Fig. 2 is a partial elevational cross-sectional view of the parts shown in Fig. 1, and at a larger scale, showing the parts in relation to provide a restricted flow through the testing tool;

Fig. 3 is a view similar to Fig. 2 showing the relation of parts to provide a full flow through the testing tool; and

2

Fig. 4 is a view similar to Fig. 2 showing the relation of parts to provide a final shut-in pressure test.

A testing tool 1, in accordance with the present invention, comprises a top sub 2 adapted to be connected to the lower end of a pipe or drill string 3 and supported by a thrust bearing 4 for rotation relative to a tubular housing 5 which includes tubular housing sections 6, 7 and 8. The lower tubular housing section 8 is adapted to be connected to the top end of suitable testing equipment 9. This testing equipment will conventionally include, in descending order, an equalizing or by-pass valve, a packer, a perforated pipe for admitting fluid, and pressure measuring means to record pressures, such as the initial and final shut-in well pressures, during a test.

Dependently connected to the top sub 2 by screw threads 11 is a tubular test mandrel 12 comprising an upper jack mandrel section 13 and a lower mandrel section 14 connected together by screw threads 15. Mounted on the bottom end of the lower mandrel section 14 by collar 16 is a downwardly opening check valve 17. Ball 18 of the check valve 17 is held against valve seat 19 by spring 20 to prevent upward flow of fluid through the lower end of mandrel 12. The lower mandrel section is, however, provided with laterally opening test ports 21 intermediate its length.

The jack mandrel section 13 has a portion 22 of enlarged diameter, the upper end of which abuts a downwardly facing shoulder 23 formed in the upper housing section 6. External jack threads 24 are formed on the lower half of jack mandrel section 13. As will be appreciated, with the mandrel 12 screwed into the top sub 2 so that the enlarged mandrel portion 22 is in engagement with the shoulder 23, no longitudinal movement of the mandrel 12 with respect to the housing 5 may take place. However, because of the thrust bearing 4, the top sub 2 and mandrel 12 may be rotated relatively to housing sections 6, 7 and 8 by the pipe string 3.

A valve sleeve 25 comprising an upper annular sleeve portion 26 and a lower annular sleeve portion 27 is mounted in the housing 5 for longitudinal, non-rotative movement therein. The upper sleeve portion 26 is provided with internal jack threads 28 adapted to engage the external jack threads 24 of the jack mandrel section 13. A spline 29 fits into registering longitudinal grooves formed in the upper housing section 6 and upper sleeve portion 26 to prevent relative rotational movement therebetween, while allowing the upper sleeve portion 26 and the lower sleeve portion 27, connected by screw threads 30, to move longitudinally with respect to the housing 5.

As is now apparent, if the housing 5 is held against rotation, as by setting of the packer, and the drill string 3 is rotated, the rotation will be transmitted to the jack mandrel section 13. The rotation of the jack threads 24 of the jack mandrel engaging the jack threads 28 of the sleeve 25 causes the sleeve to move longitudinally with respect to the housing 5, the usual right-hand rotation producing a corresponding upward travel of the sleeve.

Mounted in the lower sleeve portion 27 and carried by it are a series of annular flow controlling members 31 arranged to be positioned with respect to the test ports 21. A first annular member 31 of cylindrical configuration is snugly fitted in the lower sleeve portion 27 with its upper end engaging the bottom end of the upper sleeve portion 26. The inner cylindrical surface of member 31 is in sliding contact with the outer surface of the lower mandrel section 14. Unrestricted longitudinal passages 32 are spaced circumferentially around the member 31 and extend lengthwise through the member.

A second annular member 33 of disc-like configuration is snugly fitted in the sleeve 27 for sliding along the lower mandrel section 14 and is spaced below the member 31 by a fitted annular spacer 34. The disc 33 is provided

with circumferentially spaced, longitudinal metering passages or choke orifices 35, whereby the fluid flow through passages 35 may be restricted. Carried by the disc 33 is an O-ring 36 for sealing with the inner surface of the lower sleeve portion 27.

A third annular member 37 of cylindrical configuration is snugly fitted in the sleeve 27 and spaced below the disc 33 by a fitted cylindrical spacer 38. The member 37 is provided with unrestricted longitudinal passages 39 therethrough, the passages 39 having a cross-sectional area greater than the cross-sectional area of the metering passages 35 of disc 33, to allow an unrestricted flow of fluid passing upwardly to the test ports 21. The member 37 also slidably engages the outer surface of the lower mandrel section 14.

A lock ring 41 holds the annular members and spacers in assembled relation within the lower sleeve portion 27. Thus, there is provided a longitudinal extending flow course comprising, in succession, unrestricted passages 39, a lower chamber 42 defined by the bore of spacer 38, restricted passages 35, an upper chamber 43 defined by the bore of spacer 34, and unrestricted passages 32.

In order that the circumferentially spaced, laterally opening and downwardly slanting test ports 21 formed in the lower mandrel section 14 may provide selective fluid communication between the inside of the lower mandrel section 14 and the lower and upper chambers 42, 43, a rubber packing 14 is bonded to the lower mandrel portion 14 below the test ports 21 and a rubber packing 45 is bonded to the lower mandrel portion 14 above the test ports 21. These packings 44, 45 seal selectively with the inner surfaces of the upper intermediate and lower passage defining members 31, 33 and 37.

A rubber packing 46 is bonded to the upper portion of the jack mandrel 13 to prevent the passage of fluid between the jack mandrel and the upper housing section 6. A shear pin 47 is threaded into the upper end of housing section 6 and extends into the jack mandrel 13, and serves to prevent accidental rotation between the mandrel 12 and the housing 5.

A series of lateral plugs 48 are circumferentially spaced around the housing section 7, the plugs 48 having passages 49 formed therein opposite and slightly below the test ports 21 in the mandrel to provide fluid communication between the inside and the outside of the housing 5. Such fluid communication is prevented when the sleeve portion 27 seals off the passages 49 by reason of the O-rings 51 and 52 carried externally at either end of the sleeve portion 27 and engaging the bore of the housing section 7.

The bottommost and innermost corner of the upper sleeve member 26 is notched at 54, and an annular space 55 is provided between the mandrel section 14 and the sleeve portion 26 to allow fluid communication from the passages 32 of member 31 to the mating jack screws 24 and 28.

In an exemplary operation, the top sub 2 of the testing tool is turned with respect to the housing 5 to put sleeve 25 in its lowermost position. The testing tool is then assembled as in Fig. 1 with its upper end connected to pipe string 3 and its lower end to the testing equipment 9, and is lowered into a well bore. The testing equipment is sealed against the well bore, as by setting the packer, thus preventing the housing 5 from rotating relative to the well bore. Fluid entering the housing 5 from the testing equipment 9 is prevented from entering mandrel 12 because the upper valve sleeve member 31 is sealed across the test ports 21 to close them. The fluid may pass through the longitudinal passages 39, 35, 32, notch 54 and annular space 55 to the jack threads 24 and 28. These threads are not fluid tight, and thus the well fluid may pass through the engaging screw threads but not beyond packing 46. With well fluid on

both sides of the jack threads, unbalanced loading of the threads by hydrostatic pressure is avoided.

As the well fluid is prevented from passing up through mandrel 12, the initial shut-in pressure of the well may be taken by the subsurface pressure recording means (not shown).

Torque is now applied to the well string, usually in a right-hand or clockwise sense, and the shear pin 47 is sheared to allow relative rotational movement between the mandrel 12 and the housing 5. The well string is turned, say, through seven revolutions, thus causing the sleeve 25 to move upwardly until it reaches the position shown in Fig. 2. As the upper chamber 43 is now opposite the test ports 21, the well fluid may now flow upwardly from the lower end of housing 5 through the large diameter passages 39 of member 37, through the metering passages 35 of disc 33 and through the test ports 21 into the mandrel 12. In this position a metered flow test may be had and production from the formations commenced without shock. The O-ring 36 and the rubber packing 44 prevent the passage of fluid around the outer and inner peripheries of disc 33, respectively, despite the pressure drop across the disc.

Turning the well string through, say, seven more revolutions brings the sleeve 25 upwardly to the position shown in Fig. 3. In this position, the lower chamber 42 is opposite the test ports and full flow of the well fluid is allowed through the passages 39 of the lower member 37 and the test ports 21 into mandrel 12. It may be noted that the lower housing section 8 affords a full annular flow passage about the check valve 17.

Turning the well string through, say, seven more revolutions brings the sleeve 25 upwardly to the position as shown in Fig. 4. In this position the test ports 21 are again sealed, this time by valve sleeve member 37, and the final shut-in pressure may be measured.

If it is desired to provide reverse circulation for the well, the well string is turned through, say, seven more revolutions to raise O-ring 52 carried by the lower sleeve portion 27 above the circulating ports 49 and the valve sleeve member 37 above the test ports 21, thus allowing free fluid communication between the interior of mandrel 12 and the exterior of the housing 5.

As may be appreciated, valve sleeve members 31 and 37, spacers 34 and 38, and disc 33 can be arranged easily in different orders or the lengths of these elements can be changed, or more discs may be added to provide different sequences of operation without a major alteration of the tool. Another advantage of the invention is that the initial fluid passing longitudinally through the tool is metered before its direction is changed, thus helping to prolong the life of the test ports 21.

The length of travel of the sleeve 25 is limited by the original distance allowed between the lower edge of the enlarged mandrel portion 22 and the top of the upper sleeve portion 26. When the top of the sleeve portion 26 contacts the mandrel portion 22, the sleeve portion 26 then acts as a stop nut and prevents further rotation of the mandrel 12 because of the spline 29. The testing equipment below the tool 1 may then be rotated by the pipe string for ready withdrawal of the equipment from the borehole.

If desired, any of the various packings may alternatively be mounted on the member with which a seal is effected. The O-ring 52 may be so disposed in relation to the circulating ports 49 as to open these ports for equalization of pressure above and below the packer while the test ports are still closed.

Accordingly, while an exemplary embodiment of the invention has been shown and described, various changes may be made in its construction by those skilled in the art without departing from the spirit of the invention, the scope of which is defined in the appended claims.

I claim:

1. A well testing tool for connection in a pipe string,

comprising a tubular housing, a tubular mandrel extending within said housing and having a lateral test port intermediate its length, a sleeve portion within said housing movable longitudinally relative to said mandrel and having longitudinally spaced upper and lower valve members for selectively closing said test port, said lower valve member having a longitudinal passage therethrough, and means for moving said sleeve portion relative to said mandrel from a position with said upper valve member closing said test port through a position with said test port communicating through said passage to a position with said lower valve member closing said test port.

2. A well testing tool for connection in a pipe string, comprising a tubular housing, a tubular mandrel rotatably mounted within said housing and having a lateral test port intermediate its length, a sleeve non-rotatably received within said housing and threadedly coupled with said mandrel for relative longitudinal movement with respect to said mandrel when said mandrel is rotated, and upper and lower longitudinally spaced valve members carried by said sleeve for selectively closing said test port, means to seal said valve members with respect to said mandrel, said lower valve member having a longitudinal passage therethrough for admitting fluid to said mandrel when said valve members are spaced above and below said test port.

3. A well testing tool for connection in a pipe string, comprising a tubular housing, a tubular mandrel rotatably mounted within said housing and having a lateral test port intermediate its length, and a sleeve non-rotatably received within said housing and threadedly coupled with said mandrel for relative movement longitudinally along said mandrel when said mandrel is rotated, said sleeve having longitudinally spaced upper and lower valve portions for successively closing said test port and having a passage therethrough communicating with a space intermediate said valve portions, said mandrel having its lower end closed against upward flow of fluid and spaced inwardly of said housing for defining an annular chamber through which fluid may flow longitudinally into said passage.

4. A well testing tool for connection in a pipe string, comprising a tubular housing having a circulating port therethrough, a tubular mandrel rotatably mounted within said housing and having a lateral test port intermediate its length, a sleeve non-rotatably received within said housing and threadedly coupled with said mandrel for longitudinal movement relative to said mandrel and housing between upper and lower limiting positions when said mandrel is rotated, means to seal said sleeve across said circulating port except in said upper limiting position, and longitudinally spaced upper and lower valve means carried by said sleeve for selectively closing said test port in accordance with the position of said sleeve, said lower valve means having a longitudinal passage therethrough for admitting fluid through said test port in an intermediate position of said sleeve, said test port being open in said upper limiting position of said sleeve to place the interior of said mandrel in communication with the exterior of said housing through said circulating port.

5. A well testing tool for connection in a pipe string, comprising a tubular housing, a tubular mandrel rotatably mounted in said housing and having a lateral test port intermediate its length, a sleeve non-rotatably mounted within said housing and in threaded connection with said mandrel for longitudinal movement therealong when said mandrel is rotated, spaced upper and lower annular valve members carried within said sleeve and defining a fluid communication space for communication with said test port, said lower valve member having a longitudinal passage therethrough communicating with the said space intermediate said valve members, and an annular flow restricting member carried within said sleeve intermediate said upper and lower valve members for dividing said space into upper and lower chambers in

restricted fluid communication, whereby flow of fluid upwardly through said passage and into said mandrel is restricted when said upper chamber is opposite said test port and is relatively unrestricted when said lower chamber is opposite said test port.

6. A well testing tool comprising a tubular housing, a tubular mandrel mounted within said housing having a lateral test port, a sleeve mounted between said housing and said mandrel and adapted to move longitudinally therebetween, said sleeve having a portion thereof in sealing engagement with said mandrel, a first annular member carried by said sleeve in another portion thereof and in sealing engagement with said mandrel, said first annular member having a restricted longitudinal passage therethrough and a second annular member carried by said sleeve, said second member being spaced from said first annular member and in sealing engagement with said mandrel, said second annular member having a longitudinal passage therethrough of greater cross-sectional area than said restricted passage.

7. A well testing tool comprising a tubular housing, a tubular mandrel mounted within said housing, a lateral test port in said mandrel, a sleeve mounted between said housing and said mandrel for movement longitudinally thereof, means for moving said sleeve along said mandrel, a first annular member carried by said sleeve and adapted to engage said mandrel and to seal said test port when in register therewith, a second annular member carried by said sleeve and spaced longitudinally of said first annular member, said second annular member being arranged sealingly engaging said mandrel below said test port and having a restricted passage therethrough, a third annular member carried by said sleeve and spaced below said second annular member, and said third annular member adapted to engage said mandrel and to seal said test port when in register therewith, said third annular member being provided with a passage therethrough of greater diameter than said restricted passage.

8. A well testing tool comprising a tubular housing having a circulating port therethrough, a tubular mandrel rotatably mounted within said housing and having a lateral test port, a sleeve sealingly engaging the inner surface of said housing and adapted to move longitudinally between two extreme positions, a first annular member mounted in said sleeve for sealing engagement with said mandrel and adapted to seal said test port when said sleeve is in its lowermost position relative to said mandrel, a second annular member mounted in said sleeve and spaced below said first annular member for sealing engagement with said mandrel, a restricted longitudinal passage through said second annular member, and a third annular member mounted on said sleeve and spaced below said second annular member for sealing engagement with said mandrel, said third annular member being adapted to seal said test port when in register therewith and to uncover said test port when said sleeve is in its upper extreme position, said third annular member having a longitudinal passage therethrough of greater cross-sectional area than said restricted passage, said circulating port being uncovered by said sleeve when said sleeve is in its upper extreme position to establish fluid communication between the interior of said mandrel and the exterior of said housing.

9. A well tool comprising a tubular housing, a tubular mandrel rotatably mounted within said housing and having a lateral test port intermediate its length and external threads spaced above said test port, a sleeve mounted between said housing and said mandrel and having internal threads on its upper end engaged with said external threads, means for preventing rotational movement of said sleeve with respect to said housing while permitting relative longitudinal movement therebetween whereby rotational movement of said mandrel with respect to said housing causes said sleeve to move longitudinally with respect to said housing and said mandrel, seal means car-

ried by said mandrel above and below said test port, a first annular member mounted in said sleeve for engaging said seal means to close said test port when in register therewith, a second annular member mounted in said sleeve and spaced below said first annular member for engaging said seal means when spaced below said test port, said second annular member having a restricted passage therethrough, and a third annular member mounted in said sleeve and spaced below said second annular member for engaging said seal means to close said test port when in register therewith, said third annular member being provided with a passage therethrough of greater diameter than said restricted passage of said second annular member.

10. A well tool comprising a tubular housing, a tubular mandrel rotatably mounted within said housing in sealed relation therewith and having a test port intermediate its length, a sleeve mounted between said housing and said mandrel and in threaded connection with said mandrel, means for preventing rotational movement of said sleeve with respect to said housing while permitting relative longitudinal movement therebetween whereby rotational movement of said mandrel with respect to said housing causes said sleeve to move longitudinally with respect to said mandrel, seal means carried above and below said test port by said mandrel, a first annular member mounted in said sleeve for engaging said seal means to close said test port when in register therewith, said first annular member having a longitudinal passage therethrough, a second annular member mounted in said sleeve and spaced below said first annular member for defining upper and lower annular chambers, said second annular member having a restricted longitudinal passage therethrough to place said chambers in communication, a third annular member mounted on said sleeve and spaced below said second annular member by said lower chamber for en-

gaging said seal means to close said test port when in register therewith, said third annular member being provided with a longitudinal passage therethrough of greater diameter than said restricted passage of said second annular member to supply fluid through said chambers and passages externally along the length of said mandrel for controlled admission to said test port.

11. A well testing tool comprising a tubular housing, a tubular mandrel rotatably mounted within said housing and having a test port intermediate its length, a sleeve non-rotatably received within said housing for movement longitudinally between two extreme positions, means for moving said sleeve longitudinally upon rotation of said mandrel, an upper annular valve member slidably received in said sleeve for closing said test port when said sleeve is in its lowermost position relative to said housing and said mandrel, an annular flow restricting member slidably received in said sleeve in sealing engagement therewith and having a restricted longitudinal passage, a lower annular valve member slidably received in said sleeve for closing said test port when in register therewith, said lower valve member having formed therethrough a longitudinal passage of greater cross-sectional area than said restricted passage, spacer means slidably received in said sleeve intermediate said flow restricting member and said valve members to define upper and lower chambers for successive registry with said test port, and means for retaining said members and said spacer means in said sleeve.
